UNITED STATES PATENT OFFICE.

ARTHUR K. TAYLOR, OF BALTIMORE, MARYLAND, ASSIGNOR TO THE UNITED STATES PRINTING AND LITHOGRAPH COMPANY, A CORPORATION OF OHIO.

SHEET PILER.

Application filed June 7, 1924. Serial No. 718,509.

My invention relates to improvements in a sheet piler or lay boy, and it is intended to be an improvement over the general type of sheet pilers described and claimed in the 5 patent granted to F. E. Rich on July 13, 1915, numbered 1,145,921, although it is not limited in its application to such a machine. It often happens in the use of a piler in which slow acting gears control the position 10 of the receiving table, that the end of a run on the press is reached before the piling table is full, and consequently, before it is lowered onto the trucks under the table. The table, when even partially filled, is so heavy that 15 it would be impracticable to handle it manually. It is customary, when it is desirable to lower the table more rapidly than the sheet delivery mechanism driven from the printing machine does it, to turn some of the 20 driving gears by hand, but it has been found to be a very slow process, and I have therefore devised a means of lowering the table more rapidly without doing away with the advantages of the slow acting gears. I attain 25 this, and other objects and advantages, by the mechanism illustrated in the accompanying drawings, in which—

Figure 1 is a vertical side view of the entire machine; Fig. 2 is a vertical end view 30 with certain parts broken away. Fig. 3 is a partial sectional view of the gearing on line 3—3 of Fig. 2 looking in the direction of the arrows; Fig. 4 is a detail view, showing the pawl disengaging means. Figure 5 is a detail view of the brake mechanism on 35 line 5—5 of Figure 2.

Similar numerals refer to similar parts throughout the several views.

Table or plate 11 is supported on T beams 40 21, having at their ends hooks 20, over which eyes 19 of the inner ends 18 of chains are passed. These chains are reeved over pulleys 17 having notched peripheries to hold them. The outer ends 22 of the chains have hand grips 23. Pulleys 17 are fast on shafts 15, which are mounted in bearings 14 on horizontal bars 12 supported on standards 13.

Shafts 15 have ratchet wheels 24 fast on 50 them near their outer ends. Worm wheels 26 are rotatably mounted on the shafts. Pivoted to these worm wheels, and held in engaging position by springs, are pawls 25 coacting with their respective ratchet wheels. Pawls 25 have outwardly extending pins

43, as shown in Figs. 3 and 4. Fast to worm wheels 26 are housings 44 which have rolled over outer rims, near shafts 15, as shown at 45. Under these rims are rotatably mounted rings 46 having handles 47 screwed to them. 60 Rings 46 have notches 48 and 49 in their rims. Pins 43, when resting in notches 48, permit their pawls to operate on the teeth of the ratchet wheels, but when rings 46 are rotated so that the pins are in notches 65 49, the pawls will be raised out of operative contact with their ratchet wheels.

Supported in bearings on brackets across the back of the machine is a shaft 28 having worms 27 fast to it which mesh with worm 70 wheels 26. On one end of shaft 28 is a ratchet wheel 29. Pivoted to the shaft is a lever 32 having pivoted to it at 31 a pawl 30 which works on ratchet wheel 29. Lever 32 has a counter-weight 33. To lever 32 is 75 pivoted a rod 34, which is adjustably and pivotally held in arm 35, which in turn, is pivoted to the other end of the machine at 36 and is operated from the printing press by rod 37. To the other end of shaft 28 a 80 long hand crank 42 is fast.

Beyond worm wheels 26 and fixed on shafts 15 are ratchet wheels 50, and rotatably mounted on the shafts are worm wheels 51, having spring held pawls 52 pivoted 85 thereto and working on ratchet wheels 50. A worm shaft, 53, with worms 54 is mounted in bearings on brackets across the back of the machine; this shaft is parallel with shaft 28. The worms 54 mesh with the 90 worm wheels 51. The lead of worms 54 is much greater than that of worms 27; it is, in fact, so great that the worms can be turned by the rotation of the worm wheels 51.

A drum brake 55 of conventional design 95 with the drum keyed on shaft 53 and with a pin handled screw on the brake band governs the rotation of the shaft. The brake band is held from rotation by the projection 56 moving around and coming into contact with the shaft 28 when it is in use. When it is not in use, the pin handled screw is loosened and the brake band and projection 56 hang freely on the drum.

In operation, the table is gradually lowered by the step-by-step mechanism driven from the press. When this is occurring the brake is released, the projection 56 hanging down, freely, and shaft 53 is rotated by the ratchet wheels 50 pushing around the worm 110

wheels 51 by means of pawls 52, and the worm wheels 51 in turn actuating worms 54 fixed on shaft 53. The machine is usually at rest when it is desired to lower the table rapidly. And when it is desired to lower the table rapidly the pin handled screw on the brake band is tightened and shaft 28 is reversely rotated by crank 42 sufficiently to allow the pawls 25 to be raised, after that projection 56 moves around freely until it comes into contact with shaft 28, and then the brake band remains stationary. The table then drops gradually to the trucks placed beneath, being restrained and regulated in its rapidity of dropping by the tightness of the brake band. When it is desired to raise the table, handles 23 on the chains are pulled.

While I have shown and described one embodiment of my invention it will be understood that this is shown for the purpose of illustration only and that I do not desire to be limited to the details of construction shown and described, for obvious modifications will occur to a person skilled in the art.

Having thus described my invention, what I claim as new and desire to secure by Letters Patent, is:

30 1. In a sheet piler, a table adapted to receive sheets, automatic means acting in timed relation with the delivery of sheets to the table to lower the same, means to disconnect said automatic lowering means, and 35 frictional means to govern the lowering of said base when said automatic lowering means is disconnected.

2. In a sheet piler, a vertically movable table, shafts operatively connected to said table, automatic means to drive said shafts, gears connecting said shafts and automatic driving means, manually operable means to disconnect said automatic driving means from said shafts, and means geared to said 45 shafts to control their operation when said automatic driving means is disconnected.

3. In a sheet piler, a vertically movable table, shafts operatively connected to said table, automatic means to drive said shafts, 50 gears connecting said shafts and automatic driving means, means to disconnect said automatic driving means from said shafts, a control shaft geared to said first-named shafts, and unidirectional power transmission means between said control shaft and said first-named shafts.

4. In a sheet piler, a vertically movable table, shafts operatively connected to said table, gears on said shafts, a worm gear shaft, 60 worms on said worm gear shaft which mesh with the gears on said first-named shafts, automatic means to drive said worm gear shaft, means to disconnect said automatic driving means from said first-named shafts, 65 and means geared to said first-named shafts

to control their operation when said automatic driving means is disconnected.

5. In a sheet piler, a vertically movable table, shafts operatively connected to said table, gears on said shafts, a worm gear shaft, 70 worms on said worm gear shaft which mesh with the gears on said first-named shafts, automatic means to drive said worm gear shaft, means to disconnect said automatic driving means from said first-named shafts, 75 other gears on said first-named shafts, a second worm gear shaft, worms on said second worm gear shaft which mesh with the said other gears on said first-named shafts, means to control the operation of said second worm gear shaft when said automatic driving means is disconnected.

6. In a sheet piler, a vertically movable table, shafts operatively connected to said table, gears on said shafts, a worm gear shaft, 80 worms on said worm gear shaft which mesh with the gears on said first-named shafts, automatic means to drive said worm gear shaft, means to disconnect said automatic driving means from said first-named shafts, 85 other gears on said first-named shafts, a second worm gear shaft, worms on said second worm gear shaft which mesh with the said other gears on said first-named shafts, the lead of the worms of said second worm gear shaft being greater than the lead of the worms of said first worm gear shaft.

7. In a sheet piler, a vertically movable table, shafts operatively connected to said table, automatic means to drive said shafts, 90 gears connecting said shafts and automatic driving means, pawls and ratchet wheels between said gears and said shafts, means to disconnect the pawls from their respective ratchet wheels, and means geared to said 95 shafts to control their operation when said pawls are disconnected from their respective ratchet wheels.

8. In a sheet piler, a vertically movable table, shafts operatively connected to said 100 table, automatic means to drive said shafts, gears connecting said shafts and automatic driving means, pawls and ratchet wheels between said gears and said shafts, means to disconnect the pawls from their respective 105 ratchet wheels, and means geared to said shafts, including other pawls and ratchet wheels, to control their operation when said first-named pawls are disconnected from their respective ratchet wheels.

9. In a sheet piler, a vertically movable table, shafts operatively connected to said table, automatic means to drive said shafts, 110 gears normally connecting said shafts and automatic driving means, unidirectional clutches between said gears and said shafts, and means geared to said shafts to control their operation when said gears and said shafts are disconnected.

10. In a vertically movable platform, 115

means for normally lowering said platform at a slow rate of speed, means to disconnect said first named means, additional means to regulate the lowering of said platform at a higher rate of speed when said first named means is disconnected.

11. In a vertically movable platform, means for normally lowering said platform at a slow rate of speed, said means including a driving shaft and driven shafts, means to disconnect said driving shaft from said driven shafts, additional means connected to said driven shafts to regulate the lowering

of said platform at a higher rate of speed when said driving shaft is disconnected from 15 said driven shafts.

12. In a vertically movable platform, means, including driven shafts, for normally lowering said platform at a slow rate of speed, means to disconnect said first named 20 means, a shaft geared to said driven shafts and brake mechanism on said shaft to regulate the lowering of said platform at a higher rate of speed when said first named means is disconnected.

ARTHUR K. TAYLOR.
